UNITED STATES PATENT OFFICE.

ALBERT E. THORNLEY, OF PAWTUCKET, RHODE ISLAND, ASSIGNOR TO NARRAGANSETT MACHINE COMPANY, OF PAWTUCKET, RHODE ISLAND.

PUMP.

Application filed June 3, 1926. Serial No. 113,416.

This invention relates to certain new and useful improvements in pumps and pertains more particularly to that type of apparatus using a multi-stage pump.

5 An important object of this invention is to provide an apparatus of the character described which is composed of a series of compression chambers and a multiple pump.

Another object of this invention is to provide an apparatus of the character described wherein a step by step increased compression from one chamber to another, is obtained.

Another object of this invention is to provide an apparatus of the character described in which the gear compartments of the various pumps are in direct communication with partially oil filled discharge wells whereby the wells serve as a sealing medium for the gears of the pump.

20 Another object of this invention is to provide an apparatus of the above described character having two or more sets of gears combined in tandem on a single shaft to form a multi-stage pump.

25 Another object of this invention is to provide an apparatus of the above described character having a pump made up of contiguous sections suitably bored and attached to a front plate by means of which the whole 30 pump can be set into a condensing chamber housing, whereby the whole pump unit can be assembled and tested entirely apart from the general assembly of the machine.

A further object of this invention is to 35 provide an apparatus of the type described which is simple in construction, durable and efficient in operation and one which can be manufactured at a reasonable cost.

In the drawings:—

40 Fig. 1 is a front elevation of a single compression unit, viz; a pump unit and compression chamber combined;

Fig. 2 is a top plan view of the same with the cover of the compression chamber removed, and

Fig. 3 is an end view of a complete single unit of the described apparatus.

Referring more in detail to the drawings, A designates generally the compression chamber housing and B the pump which when combined as shown in the several figures, tend to make up a complete single unit of the apparatus which is composed of two or more of these complete units.

45 The compression unit A is formed to pro-

vide a base 1 and housing 2 which is divided into a pump chamber 3 and compression chambers 4 and 5 by a horizontally disposed partition 6 and vertically disposed partition 7 cast integral with the housing. 60

Communication is had between the compartments 4 and 5 from the pump through openings 8 and 9 in the horizontal partition 6.

A pipe 10 is connected to an opening 11 in the compartment 4 through which fluid to 65 be further compressed is fed to the pump unit 13.

The fluid is drawn into the pump chamber 3 and initially compressed by one unit 12 of the multi-stage pump unit B in chamber 4 from which it passes to the next compressing unit 13 of the pump where it is further compressed and forced into the chamber 5 through the opening 9. An outlet 14 is provided in the upper wall 15 of 70 the housing of the next adjacent unit through which the compressed fluid passes to the chamber 4 of the said next compression unit similar to the one described. 75

As shown in Fig. 2 of the drawings and in dotted lines in Fig. 1, the horizontal partition is provided with upwardly extending portions which form the top of the pump chamber 3 and which conform to the top of the pump unit B. The front of the housing 85 has an opening through which the pump unit can be withdrawn and which is closed by a ring 16 that is secured to the pump unit and is bolted in place onto the housing. In order to remove the pump unit, it is therefore merely necessary to remove the bolts 90 whereupon the pump can be slid out of its chamber both easily and quickly.

It will be thus seen that a refrigerating apparatus composed of a series of compression chambers is provided in which a multi-stage pump is used, whereby the fluid is compressed and the compression stepped up from one unit to another until the desired result is obtained. 95

Further the pump unit B is formed of a series of rotors mounted in tandem upon a single shaft whereby the whole pump unit may be detached from the housing for testing the same independent of the remaining portion of the system. 105

Having thus described my invention what I claim as new and desire to secure by Letters Patent is:—

A refrigerating apparatus composed of a 110

series of independent compression units each having a housing formed with a pump chamber, a horizontal partition in each housing having an upwardly extending portion forming the top of the pump chamber, the front side of each housing having an opening, a pump in each chamber slideable through the opening and formed to be freely received in the pump chamber, means connected to the pump and removably secured to the housing and adjacent said opening to hold the pump in its chamber and whereby upon removal of said means the pump may be slid out of the chamber, a vertical partition engaged

20 to the top of the housing and forming a pair of compressed fluid and oil receiving compartments, a cover for the housing engageable with the upper edge of the partition, said horizontal partition having openings on opposite sides of the vertical partition and communicating with the pump chamber, and means to interconnect the units whereby to conduct the fluid from one unit to the next adjacent unit so as to increase the compression stage-by-stage.

25 In testimony whereof I have signed my name to this specification.

ALBERT E. THORNLEY.
